ABRADING APPARATUS

Louis B. Tuchmann and Sidney Joe Tuchmann,
Norfolk, Va.

Application April 7, 1938, Serial No. 200,735

5 Claims. (Cl. 51—194)

This invention relates to abrading apparatus and more particularly to a holder for a sheet of abrading material.

In the cleaning of metal or other surfaces, it has not been uncommon to utilize abrading material such as emery cloth, sandpaper and the like which have been applied to the surfaces to be cleaned by hand or otherwise. It has been found that when sandpaper or emery cloth is held in the hand and the surface to be cleaned rubbed with the abrasive material, the results obtained may be satisfactory for some purposes but not in all cases. For example when a more or less regular finished cleaned surface is desired, it has been found to be expedient to make use of some holder for the abrasive material when the same is applied to the surface to be cleaned. In addition, it has also occurred to those engaged in the cleaning of surfaces of abrasive materials that more satisfactory results may be obtained when a holder for the abrasive material is utilized that more or less approximates the surface contours of the surface to be cleaned. That is, when the surface to be cleaned is a plane, a block of wood in the shape of rectangular parallelepiped about which the abrasive sheet material is wrapped has frequently been made use of.

While these methods have been more satisfactory than the one which merely involved the application of the sheet of abrasive material directly to the surface to be cleaned merely through the agency of the hand of the operator or workman, and while the results obtained are slightly improved, this latter method involves considerable time and labor in its application and it has remained for applicant to provide a simple holding device for a sheet of abrasive material which, as will later be described in more detail, rapidly and effectively effects the cleaning of surfaces with a minimum of effort.

It is well known that if a good solder joint is to be had, the surfaces of the members to be joined by soldering must first be cleaned before the flux and solder is applied and the above mentioned methods of cleaning have been used in connection with the preparatory work in the art of soldering joints. Other problems have presented themselves when the surfaces to be cleaned prior to soldering are internal, as in pipe fittings, such as copper pipe fittings, which are used in large quantities today in various plumbing, air conditioning, and other hydraulic installations. One prior method of cleaning such interior surfaces involves the wrapping of sheet abrasive material about a finger of the operator which is

then inserted and oscillated within a fitting opening to effect cleaning of the interior surface. The objections to this method are obvious in that they are wasteful of time, the results are non-uniform, and it is ineffective where the orifice of the fitting is relatively small.

It is an object of the invention to provide a simple holder adapted to receive and hold a sheet of abrasive material.

It is a further object of the invention to provide a holder of simple and rugged construction adapted to receive a sheet of abrasive material from an operator, with a minimum of effort on the part of the operator, and hold it in proper abrading position.

Other objects and the nature and advantages of the invention will be apparent from the following description taken in conjunction with the accompanying drawing, wherein:

Fig. 1 is a view partly in elevation and partly in section illustrating one application of the invention;

Fig. 2 is a view in perspective of the preferred form of the sheet abrasive holder;

Fig. 3 is an end view of a modified form of holder; and

Fig. 4 is an end view of the holder shown in Fig. 2 with the sheet abrasive material in operative position on the holder.

Referring to the drawing a gear box 10 is mounted on a work bench 11 through the medium of C clamp mechanism 12 formed integral with gear box 10. Within the gear box 10 a small gear 13 and a meshing large gear 14 are operatively associated with each other in a manner such that when crank handle 15 is rotated by hand at a given speed the shaft 16 which may be formed integral with gear 13, is rotated at a much greater speed. The exposed end portion 17 of the shaft 16, externally of the gear box 10, may be generally square in cross section to cooperate with the generally square opening 18 formed throughout the length of the cylinder 19, which comprises the body portion of the preferred form of holder, see Fig. 2. A groove 20 may be formed in the surface of the cylinder 19, parallel to its axis in a manner to receive and securely hold the bent end section 21 of the spiral leaf spring 22. It is to be noted that the only portion of the spring 22 which is secured to the body portion 19 is that end portion 21 which is received within the longitudinal slot 20. The method or means for securing the end portion 21 to the body 19 may depend upon the character of the material utilized. For example, if they

both be steel this junction may be effected by welding or by other suitable means for joining ferrous metals. When the body portion 19 is a plastic, such as a phenol resin, cellulose acetate, phenol-formaldehyde, pyroxylin, urea-formaldehyde, or even hard rubber, the body portion may be cast or molded into place about the end portion 21 and simultaneously effect a secure junction therebetween.

10 In applying a sheet of abrasive material 23 to the holder, a sheet should be selected which is of a width corresponding to the width of the holder 19 or it may be cut from a larger sheet to such width. The length of the abrasive material should correspond to approximately the circumference of the cylinder 19 and perhaps a trifle longer. One end of the sheet abrasive material selected is bent back on itself to form a hood portion 24, see Fig. 4, which may then be slipped over the free end portion 25 of the spring 22 and the remainder of the sheet abrasive material wrapped about the outside of the leaf spring 22 and held in position by the thumb and forefinger of the operator until it is inserted 15 within an internal surface to be cleaned, as illustrated by way of example in Fig. 1, by T fitting 26. By wrapping the sheet abrasive material relatively tightly about the leaf spring 22, the spring is compressed toward the surface of 20 the body portion 19 and the whole assembly will then be of such a size as to facilitate the insertion of the holder and abrasive material within the opening 27 of the T fitting 26, the interior surface of which is to be cleaned preparatory to 25 a soldering operation. The T fitting 26 may have formed therein solder grooves 28 and solder openings 29 to permit the entry of solder into the grooves 28.

With the T fitting grasped firmly in one hand 30 of the operator the holder 19 and abrading material inserted within the opening 27 of the fitting, the temporary assembly is then associated with the end portion 11 of the shaft 16 as illustrated in Fig. 1 and the crank handle 15 rotated 35 by the operator with his other hand for several seconds to effect the proper cleaning of the interior surface of the opening 27 within the T fitting 26. It will be understood that when the tightly wrapped holder 19 and spring 22 is inserted in the proper position within the opening 27 and released, the spring 22 will then expand 40 and adjust itself to effect the proper bearing relationship with the surface of the opening 27 whereby the abrading material will uniformly 45 and definitely effect the cleaning of said surface.

50 A modified form of holder, illustrated in Fig. 3, may comprise a cylindrical body portion 30 about which is mounted leaf spring 31, one end of which 32 is formed to a square section tube 55 and the other end 33 free corresponding to the end portion 25 of the preferred form of holder illustrated in Fig. 2. The cylindrical portion 30 may be fabricated of the same material and in the same manner as cylinder 19 and may be secured 60 to the leaf spring 31 in the manner described in connection with the preferred form. The method of applying the sheet abrasive material to the modified form illustrated in Fig. 3 is of course precisely the same as that already described 65 in connection with preferred form and illustrated in Fig. 4.

Not only can the body portions 19 and 30 of the holders described be made of steel and plastics as already mentioned but they can be made 70 of alloys of lead, tin and zinc or even of cast iron.

Not only can the holder be fabricated in accordance with the illustration in Figs. 2 and 3, but it is conceivable that the holder, including the body portion and the spiral shaped member, might be made of a single piece, either by molding or in any other suitable way, thereby eliminating the necessity for a junction as is required in those forms of my invention illustrated in Figs. 2 and 3.

It will be understood of course that when fittings of different sizes are to be cleaned, that abrasive material holders of different corresponding sizes are to be utilized. It has been found in practice that when an "1 inch" fitting is to be cleaned, that an effective size of cylindrical body portion is $\frac{3}{4}$ inch in diameter, when a "3/4 inch fitting" is to be cleaned an effective size body portion is $\frac{3}{8}$ inch in diameter, and when an "1/2 inch fitting" is to be cleaned, $\frac{1}{2}$ inch diameter for the body portion is effective. 10 15 20

In practice it has been found that the instant invention has made for a great saving of time. By actual count it has been estimated that there are on the average, twenty-two fittings to each bathroom installation and each of these fittings 25 has at least two or three ends to be cleaned prior to soldering. It has further been estimated that approximately two or three minutes, per joint cleaned, elapses when the cleaning operation must be performed by hand. In contrast to this, 30 the time required when the cleaning operation is performed with the aid of the instant invention, is approximately 15 to 30 seconds, making for a saving of about one and three-quarters to two and three-quarters minutes per joint cleaned. 35 As there are a minimum of two joints per fitting, approximately three and one-half to five and one-half minutes are saved on the installation of each fitting. Multiplying this saving by 22, the average amount of fittings per bathroom, it will 40 be seen that one and one-half to two hours of labor are saved when the instant invention is applied to a job. To further illustrate the saving effected by the utilization of the invention, it may be said that about ten fittings may be 45 cleaned with the aid of the device in the same time that one may be cleaned by hand.

It will be obvious to those skilled in the art that various changes may be made in this device without departing from the spirit of the invention and therefore the invention is not limited to what is shown in the drawing and described in the specification but only as indicated in the appended claims.

We claim:

1. In an apparatus for use in the cleaning of inner surfaces of metal pipe fittings, a body portion generally circular in cross section, a generally spiral shaped leaf spring member generally encircling said body portion and secured thereto at one of its ends, the other end of said spring member being free, said spring member being spaced from said body portion along its length except at that end which is secured thereto, a sheet of abrasive material comprising a 60 sheet body portion and an end portion, said end portion including a section folded back parallel to the sheet body portion, said end portion engaging the free end of said spring member and said sheet body portion overlying at least a portion of the exterior surface of said spring member. 65

2. A device for use in cleaning inner surfaces of metal fittings comprising a cylindrical body portion, a generally spiral shaped leaf spring 70 75

generally encircling said body portion and secured thereto at one of its ends to said body portion, the other end of said spring being free, a sheet of abrasive material comprising a sheet body portion and an end portion, said end portion including a section folded back parallel to the sheet body portion, said end portion engaging the free end of said spring member and said sheet body portion overlying at least a portion of the exterior surface of said spring member, the axis of said generally spiral shaped leaf spring generally corresponding to the axis of said cylindrical body portion.

3. The structure recited in claim 2, said body portion being fabricated of a plastic material.

4. In an apparatus for cleaning exterior wall surfaces of metal fittings, a generally cylindrical body portion, said body portion being formed with a passage therethrough of non-circular section, a generally spiral shaped leaf spring member generally encircling said body portion and secured to said body portion at one of its ends along a line parallel to the axis of said body portion, said spring member being free at its other end, a sheet of abrasive material comprising a sheet body portion and an end portion, said end

portion including a section folded back parallel to the sheet body portion, said end portion engaging the free end of said spring member and said sheet body portion overlying at least a portion of the exterior surface of said spring member, the axis of said spring member generally corresponding to the axis of said body portion.

5. In an apparatus for use in the cleaning of metal pipe fittings, a generally cylindrical body portion and a leaf spring member, said leaf spring member generally encircling said body portion and comprising a bent portion, said cylindrical portion being secured to the bent portion of the spring member, one end of said leaf spring member being free, a sheet of abrasive material comprising a sheet body portion and an end portion, said end portion including a section folded back parallel to the sheet body portion, said end portion engaging the free end of said spring member and said sheet body portion overlying at least a portion of the exterior surface of said spring member, the axis of the generally spiral shaped portion corresponding to the axis of the body portion.
